FIG. 5

UNITED STATES PATENT OFFICE.

GRAFTON E. LUCE, OF CHICAGO, ILLINOIS.

SEGREGATOR.

Application filed July 11, 1924. Serial No. 726,032.

This invention relates to a machine that may be utilized in hacking brick and is of the segregator type.

The chief object of the invention is to produce a machine or device which is capable of receiving successively, intermittently, continuously or instantaneously a complete load of brick or the like; by clamping and raising the brick clear of the belt while in open formation and, after clamping and raising the same thereby receiving said load in open formation, position the same in a predetermined closed or set relation required for burning.

15 The chief feature of the invention consists in the construction of the segregator device whereby the same is substantially universal in its adaptability as will be more particularly pointed out hereinafter and 20 which consists in the arrangement for positioning the several brick or the like constituting the load in a predetermined final position while supported by the segregator unit as a whole. Closing the brick up both 25 ways simultaneously means that the ends of the brick do not touch until they are in position sideways, thereby obviating or eliminating distortion, breakage, or swedging of the ends of the brick.

30 When thus arranged there is secured the desired openings between the several brick to facilitate drying or burning thereof without disturbing the spaced relation otherwise.

35 The full nature of the invention will be understood from the accompanying drawings and the following description and claims:

In the drawings, Fig. 1 is a top plan view 40 of the segregator construction showing the same in the extended or filling position and with a complete load. Fig. 2 is a side elevational view of a portion of the mechanism shown in Fig. 1 and illustrates the 45 same in the same position. Fig. 3 is a view similar to Fig. 1 and of the same parts and in the contracted or pre-arranged position. Fig. 4 is a view similar to Fig. 2 but illustrates the parts in the position corresponding to that illustrated in Fig. 3. Fig. 5 is a top plan view of the segregator unit, the extended and contracted limiting positions being shown by dotted outlines. Fig. 6 is a plan view of the limiting linkage

shown in the extended position. Fig. 7 is 55 a similar view of the same parts in the retracted position.

In brick making practice, although the invention herein disclosed is not to be understood as limited particularly to brick but is 60 adapted to operate upon other articles similar thereto, bricks are formed by a die which discharges on to a belt or movable conveyor commonly termed in the art an "offbearing" belt. The bricks are removed 65 from the belt and placed in a predetermined position upon the drier or kiln cars. These kiln cars are usually adapted to contain eight courses of brick high, the brick in each course being alternately positioned at right 70 angles to those through the adjacent courses and previously deposited. The courses usually are adapted to contain eight bricks positioned end to end the long way of the car and four bricks placed end to end the short 75 way of the car. Each car, therefore, contains eight courses long and twelve courses wide, or ninety-six brick to each course. With eight courses high the car would contain seven hundred and sixty-eight (768) 80 brick. When two cars are positioned side by side they would contain twice ninety-six or one hundred and ninety-two brick to the course.

Since the bricks are arranged alternately in the several courses, it will be understood that the length of each brick supports the widths of three bricks and thus in alternate courses there will be a front of eight bricks in length and twenty-four bricks in end. If two standard cars be positioned side by side, it will be apparent that said courses are adapted to receive twenty-four rows of 85 eight bricks, each placed end to end. It will be apparent, therefore, that 192 bricks 90 will require a substantially square frame and will completely fill a single course upon two adjacently positioned drier or kiln cars. By turning the segregator frame prior to releasing the brick, the arrangement of the brick will be such that they will be staggered in alternate courses. In brick making practice, it is customary to have the brick when positioned end to end abut each other, but when positioned side to side to be 100 spaced slightly from each other.

The segregator, therefore, is adapted to contain any number of individual brick or

the like article engaging constructions, but herein 192 of these constructions are shown provided and associated together. It will be understood that generally the drier cars 5 are constructed with ends and no sides and are of such dimensions that there is but little clearance at each side after the standard number of bricks have been positioned thereon. For operating purposes, however, some clearance is required between the individual brick engaging constructions. Since it is relatively impractical, although not impossible to construct a device which will permit the brick to be handled without 10 the supporting mechanism being positionable within the car when releasing the brick, the desirable construction is that the entire mechanism should be of smaller dimensions than those of the car. The result of satisfying these two contrary desirable conditions of clearance in loading and compactness in unloading is the present segregator construction which is adapted to include a support that is extensible and 15 which is associated with each of the individual brick-engaging means for engaging the brick or the like article when in extended relation and for depositing brick or the like when in contracted relation. 20 The segregator construction, as previously stated, is herein illustrated adapted to hold or handle 192 articles, such as brick or the like. These brick-engaging elements are arranged in rows of eight each, twenty-four rows being provided and the outside dimensions are substantially that of a square when the support is extended and contracted, although the outline may be rectangular without in any way departing 25 from the invention, since for certain conditions the several movements in two transverse directions will not be equal. Herein, however, the mechanism is shown adapted for substantially equal movement. With 30 the brick-engaging constructions arranged in rows of eight each and twenty-four rows side by side, it will be understood that the same is adapted to operate upon bricks presented by an offbearing belt or the like in any one of the following relations: one, two, 35 three, four, six, eight, twelve or twenty-four columns side by side. Likewise, since there are eight individual constructions in a row, it will be apparent that the segregating device is adapted to simultaneously pick up 40 bricks presented individually, two, four or eight at a time, or if presented continuously in row formation. It will be readily apparent that the segregator is substantially 45 universal in its adaptability, since it can operate upon brick presented by the offbearing belt in many relationships, for example, two columns of brick, each column presenting four bricks intermittently, or for 50 another example operating upon eight col-

umn of brick, each being continuous, or for still another example, operating upon twelve columns of brick presented in sets or rows of eight each.

With this preliminary description of the devices with which the segregator is associated and the work that the segregator is desired to perform, reference will now be had to the detailed construction of the segregator elements. 75

In the drawings 10 indicates the base which is supported or suspended by a post or upright 11 suitably secured thereto. The base 10 is provided upon two opposite and parallel edges with a T-shaped depending guide 12 and upon its upper surface and upon the adjacent and parallel edges with a pair of parallel T-shaped guides 13. The base 10 suitably supports a power motor 14 which carries a spiral gear 15 adapted to drive another spiral gear 16 upon the shaft 17, which shaft carries another spiral gear 18. The spiral gears 16 and 18 are adapted to mesh with the spiral gears 19 and 21 respectively carried by the shafts 90 20 and 22. The shaft 23 carries a pair of spiral gears 24 and 25 which mesh with spiral gears 26 and 27 carried upon the opposite ends of the shafts 22 and 20 respectively. The resultant construction is a 95 closed spiral gear drive power operable by the motor 14, for extension and contraction of the brick engaging supports. Each of the shafts 17, 20, 22 and 23 are extended and terminate in a pinion 28. As shown clearly in Figs. 2, 4 and 5, half of the pinions are positioned above the base plate 10 and half are positioned below the base plate 10. Slidably supported upon each of the T-shaped upwardly extending projections or 100 guide members 13 are a pair of outwardly extensible arms 29 having the T-shaped groove 30. The upper surface of the arm 30 is toothed as at 31 to provide a rack with which meshes one of the pinions 28. Another arm 32 is provided with a T-slot 33 for receiving the suspending T-shaped guide and support 12 previously described. The lower face of these members 32 are also toothed as at 34 to form a rack and are 105 adapted to mesh with the pinions 28. It will be readily apparent from the foregoing that whenever the motor 14 is energized, the power transmitted through the pinions 28 will either simultaneously retract the 110 transversely positioned supports 29 and 32 or will simultaneously extend the same, and herein to the same extent.

Each of the arms 29 terminate in a depending member 35 which is provided with an opening 36 in its lower end, and said opening is adapted to slidably receive a sleeve 37. The sleeve 37 in turn is supported by a sleeve 38, which in turn is slidably supported by a tubular shaft 39. The sleeve 125 130

37 also supports a shaft 40. The foregoing construction, to-wit, sleeves 37, 38 and 39 and shaft 40, see Fig. 5, constitutes one-half of the elongated shaft or support which 5 supports 24 of the individual brick-engaging constructions.

Each of the arms 32 at its end includes a depending arm 41 apertured as at 42 to slidably support a sleeve 43 carried by a 10 tubular shaft 44, and said sleeve 43 also supports a shaft 45. The foregoing constitutes but half of the shaft adapted to support eight brick constructions constituting a row of brick in end formation. The foregoing 15 telescopic arrangement, therefore, includes eight telescopic shafts, each including members 37, 38, 39 and 40 and 24 transversely positioned telescopic shafts including members 43, 44 and 45. It will be apparent that outward movement of the members 32 will cause the outermost shafting, including members 43, 44 and 45, to move, and since the several constructions are telescopically arranged, the entire mechanism 20 will be extended in that direction. Similarly, if the members 29 are extended, said extension causes the outermost shafting, including the members 37, 38, 39 and 40 to move outward together with the others intermediate the same. The shafting will telescope upon reverse movement. The resultant construction is that all of the shafting is simultaneously extended or contracted 25 and without interference.

Reference will now be had particularly to Figs. 2 and 4. In said figures one form of brick or similar article engaging element is illustrated, and herein the brick is indicated by the numeral 46. The brick or 30 similar article is adapted to be engaged or clamped by a pair of fingers or plate members 47, and these plate members are actuated by mechanisms forming no part of the present invention and are suitably supported by the supporting or saddle construction 48. The supporting construction 48 is provided with two transversely positioned openings 49 and 50 which receive the transversely positioned shafting. It will be understood that each of the supports 48 is supported by two transversely positioned shafts. Some of these members are slidably supported upon said shafting and others are fixedly supported thereby as necessary or 55 desired.

The means for insuring accurate spacing includes suitable linkage. These links have elongated openings at each end. The distance between the openings in each link 60 constitutes the minimum clearance between the shafting in the contracted or telescopic position. The distance from the farthest points on the elongated slots of the link constitutes the maximum distance between the 65 units. It will be apparent that these links

need not necessarily be of the same length or size and will not be of the same opening diameter, for the shafting may not be of the same diameter. It will only be necessary to provide two transverse sets of linkages, but for equal movement two parallel sets are utilized, and these are associated with the outer ends of the several shafts. When the shafting is in the contracted or telescopic position, the linkages are in their collapsed position. It will be apparent that adjacent links are alternately offset from each other. When the shafting is extended, the links are extended and limit the extreme movement of each of the several shafts. By the foregoing construction, the position of each brick-engaging unit is accurately determined in the extended and contracted positions, which are the two essential positions.

The invention claimed is:

1. In a segregator, the combination of a supporting base, an extensible shaft, and means supported upon said base for movement parallel to said shaft for changing the length thereof.

2. In a segregator, the combination of a supporting base, a plurality of extensible shafts, said shafts being positioned parallel to each other, and means supported upon said base for movement parallel to said shafts for simultaneously changing the length thereof.

3. In a segregator, the combination of a supporting base, an extensible shaft, another shaft positioned transversely of said extensible shaft, and means supported by said base for movement parallel to the said extensible shaft, whereby movement of the moving means through the second mentioned shaft changes the length of the extensible shaft and moves the second mentioned shaft into a position parallel to its first position.

4. A device of the character defined by claim 3, characterized by the second mentioned shaft being extensible and the addition of a second moving means supported upon said base for movement transverse to the first mentioned moving means whereby movement of the second moving means through the first mentioned shaft changes the length of the second mentioned extensible shaft and moves the first mentioned shaft into a position parallel to its first position.

5. In a segregator, the combination of a plurality of groups of parallel positioned shafts, said groups being positioned transversely of each other, a plurality of individual members each having a connection with two of the transversely positioned shafts at the projected intersection thereof, and means for moving one group of parallel positioned shafts into positions parallel to

their original position for moving the members with respect to the transversely positioned shafts.

6. A device as defined by claim 5, characterized by the addition of means for securing the parallel movement of the transversely positioned or second group of shafts into positions parallel to their original positions for moving said members with respect to the first mentioned group of parallel positioned shafts.

7. A device as defined by claim 5, characterized by the addition of means for securing the parallel movement of the transversely positioned or second group of shafts into positions parallel to their original positions for moving said members with respect to the first mentioned group of parallel positioned shafts, and means for causing simultaneous actuation of said shaft moving means, whereby each of the members is moved simultaneously in a resultant direction angular to the parallel and transverse positionings of said shafts and from its initial projected intersection position.

8. A device of the character defined by claim 5, characterized by means associated with all of one group of shafts for limiting the parallel positioning movement thereof.

9. A device of the character defined by claim 5, characterized by the addition of means for securing the parallel movement of the transversely positioned or second group of shafts into positions parallel to their original positions for moving said members with respect to the first mentioned group of parallel positioned shafts, means associated with all of one group for limiting the parallel positioning movement thereof, and transversely positioned means associated with the transversely positioned group of parallel shafts for limiting the parallel positioning movement of said last mentioned group.

10. A device as defined by claim 5, characterized by the addition of means for securing the parallel movement of the transversely positioned or second group of shafts into positions parallel to their original positions for moving said members with respect to the first mentioned group of parallel positioned shafts, means for causing simultaneous actuation of said shaft moving means, whereby each of the members is moved simultaneously in a resultant direction angular to the parallel and transverse positionings of said shafts and from its initial projected intersection position, and the addition of transversely positioned means associated with the transversely positioned parallel groups of shafts for limiting the parallel positioning movement in the transverse directions.

11. A device of the character defined by

claim 5, characterized by an extensible construction of the second mentioned group of shafts, whereby parallel movement of the first group of shafts into positions parallel to their original position simultaneously changes the length of the other group of shafts.

12. A device as defined by claim 5, characterized by the addition of means for securing the parallel movement of the transversely positioned or second mentioned group of shafts into position parallel to their original positions for moving said members with respect to the first mentioned group of parallel positioned shafts, all of said shafts being of extensible character whereby said parallel movement of each group of parallel shafts secures change of length in the other and transversely positioned group of parallel shafts.

13. A device as defined by claim 5, characterized by the addition of means for securing the parallel movement of the transversely positioned or second mentioned group of shafts into positions parallel to their original positions for moving said members with respect to the first mentioned group of parallel positioned shafts, and means for causing simultaneous actuation of said shaft moving means, whereby each of the members is moved simultaneously in a resultant direction angular to the parallel and transverse positionings of said shafts and from its initial projected intersection position, all of said shafts being of extensible character, whereby all of said shafts are simultaneously changed in length through the parallel movement of shafts positioned transversely thereof.

14. In a segregator, a plurality of similar members arranged in a plurality of parallel rows, a shaft supporting each of the parallel rows, said members being longitudinally slidable thereon, means for moving said shafts into positions parallel to their original positions, and means for moving said members upon said shafts.

15. In a segregator, a plurality of similar members arranged in tandem and parallel arrangement in a plurality of transverse parallel row arrangements, a shaft supporting each of the members arranged in row formation, said members being slidable longitudinally thereon, and means for moving the transversely positioned shafts into positions parallel to their original positions for moving each of the members from the initial positions to an ultimate position in a direction angular to the longitudinal movement of said members upon the shafts.

In witness whereof, I have hereunto affixed my signature.

GRAFTON E. LUCE.
